ATTORNEY

UNITED STATES PATENT OFFICE.

REGINALD A. HECKROTH, OF DELHI, NEW YORK.

DESIGN FOR A PAIR OF EYEGLASSES.

50,385.

Specification for Design.

Patented Feb. 27, 1917.

Application filed November 10, 1916. Serial No. 130,678. Term of patent 14 years.

To all whom it may concern:

Be it known that I, REGINALD A. HECKROTH, a citizen of the United States, residing at Delhi, in the county of Delaware and State of New York, have invented a new, original, and ornamental Design for Eyeglasses, of which the following is a specification, reference being had to the accompanying drawing, forming a part thereof.

The figure is a perspective view of an eyeglass, showing my new design.

I claim:

The ornamental design for a pair of eyeglasses, as shown.

REGINALD A. HECKROTH.

Witness:

EDWARD O'CONNOR.
